[57] CLAIM

The ornamental design for a surface portion of shoe outsole, as shown and described.

DESCRIPTION

FIG. 1 is a bottom plan view of a portion of a surface portion of a shoe outsole showing my new design;

FIG. 2 is an enlarged profile view taken generally along line 2—2 of FIG. 1;

FIG. 3 is an enlarged profile view taken generally along line 3—3 of FIG. 1;

FIG. 4 is a profile view taken generally along line 4—4 of FIG. 1; and,

FIG. 5 is a perspective view of the surface portion of a shoe outsole of FIG. 1.

The broken line showing of the remainder of the shoe outsole is for illustration purposes only and forms no part of the claimed design.
